CLAIM

The ornamental design for a carriage for exercise rack, as shown and described.

DESCRIPTION

FIG. 1 is a top, front, left perspective view of a carriage for exercise rack showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, front, right perspective view thereof; and,

FIG. 9 is a top, front, left perspective view thereof, shown in a condition of use.

The broken lines in FIGS. 1-8 show portions of the carriage for exercise rack which form no part of the claimed design. The additional broken lines shown in FIG. 9 are to show environmental structure and form no part of the claimed design.
